BUILDING STRUCTURE

Henry C. Mortenson, Silver Spring, Md.

Application February 13, 1945, Serial No. 577,643

7 Claims. (Cl. 189—1)

1

This invention is directed to an improvement in building constructions and more particularly to the formation of certain particular units formed for interfitting and interlocking to provide a building structure.

The primary object of the invention is to provide structural building units, particularly and peculiarly formed for interfitting assemblage, with the interfitting parts of the units providing a positive interlock to prevent separation under any and all usual strains to which the building structure may be subjected in use.

A further object is to provide interlocking structural units that are so designed as to require a minimum of types or forms of such units, ordinarily limited to two, which, through their edge formations, are capable of interlocking assemblage for use in substantially all parts of the building structure, that is, the walls, floors, the roof, the interior partitions and other main parts of the building, without material change in the forms of such units.

A further object of the invention is to provide one such unit that is capable of serving as a main unit in providing the walls, floor, ceiling and roof, and the provision of another unit for interlocking with, and serving to position, the main units and provide structural bases and supports with relation to the main units.

A further object of the invention is to provide main structural units capable of being arranged as a double wall structure, and auxiliary units for tying together the main units in each wall as well as cooperating with respective auxiliary units to tie together spaced walls, such cooperative auxiliary units being wholly free of contact, one with the other, whereby the respective walls are wholly free of thermal conducting contact, are spaced to provide an effective intermediate insulating area and also provide channels for the reception of electric conduits or pipes.

A further object of the invention is to provide auxiliary units for tying the respective walls in spaced relation, the respective auxiliary units having portions that extend in parallel adjacent relation with the length of one auxiliary unit of each pair interrupted to provide supports for the floor structure while the other such auxiliary unit of each pair is continued above the floor structure to provide a partition in the floor space and to extend to and afford support for the roof.

A further object of the invention is to provide a locking section which, following assemblage of the main units and the auxiliary units may be

2

interfitted with the ends of such units to frictionally cooperate and maintain the units against possible separation under ordinary building strains.

5 A further object of the invention is to provide main units and auxiliary units which may be assembled to provide a roof structure which, through the use of auxiliary tying clips is rigidly tied to the building structure proper, and effectively supported from and by that building structure.

10 A further object of the invention is to provide structural building units and necessary tie elements of sheet material, preferably metal such as aluminum, steel, or the like, varying in gauge according to the strength required and incident to that particular and peculiar locking cooperation of ready and convenient assemblage and desired assemblage to thereby provide a true portable structure without the necessity of auxiliary fastening elements; the formations of the units however, being such as to facilitate the use of more permanent fastening elements, such as screws, or even welding in order when desired, to 15 provide a more permanent building structure.

20 The invention is illustrated in the accompanying drawings in which:

Fig. 1 is a fragmentary exploded view in perspective of the three principal units designed in accordance with the present invention for the formation of the wall, floor, ceiling and roof of the building structure;

25 Fig. 2 is a fragmentary cross-sectional view taken on a horizontal plane through a double walled building constructed in accordance with the present invention;

30 Fig. 3 is a fragmentary cross-sectional view taken on a vertical plane through a double walled building constructed in accordance with the present invention;

35 Fig. 4 is a fragmentary cross-sectional view taken on a plane corresponding to line 4—4 of Fig. 3.

40 Fig. 5 is a fragmentary view in perspective of modified units for use in floor construction;

Fig. 6 is a fragmentary view in perspective of a corner support and brace unit;

45 Fig. 7 is a fragmentary view in perspective of a coupling or fastening element on a surface unit for connection with the corner unit;

Fig. 8 is a fragmentary cross-sectional view of the connection between a surface unit and a corner brace; and

50 Fig. 9 is a fragmentary view in perspective of a

modified locking unit for use with locking a roof constructed in accordance with the invention.

A complete building, in accordance with the present invention, may be constructed from a plurality of prefabricated members that are formed from sheet material and adapted to interlock to provide a rigid construction.

These pre-fabricated members, preferably comprise a minimum of different types of elements and, as shown in Fig. 1, may include three basic units, namely a main panel unit 1, an auxiliary retaining unit 2 and a locking unit 3, obviously, in certain uses of these units other suitable tying or connecting elements may be employed and may be of more or less conventional form.

The main panel unit 1 is made of a sheet material, preferably metal, as aluminum, steel or the like, the proportions of which, but not the configuration, may vary to meet the use of the unit in certain parts of the building structure. The main unit 1 comprises a main face section 4 formed at the longitudinal edge with a rearwardly extending (considering the use of the unit) angular projection 5 from the terminal of which the unit is formed to present a rearwardly inclined spacing section 6 and at the end of the latter further formed to provide a forwardly inclined locking section 7. The opposite longitudinal edge of the main face 4 is provided with a rearwardly extending offset 8 that is connected with a locking section 9 which is rearwardly inclined. When two panel units 1 are placed in position, their respective inclined locking sections 7 and 8 are substantially parallel forming locking sections at the adjacent ends of the main units, and while they extend in opposite directions from the plane of the main units, the free edge of either section 7 or 8 does not extend forwardly beyond the front faces 4 of the main units 1.

The auxiliary unit 2 includes a face portion 10 that is adapted to fit between and in the plane of the face portions 4 of the main units 1. One longitudinal edge of the face portion 10 is folded rearwardly to form a right angular flange 11 and the opposite longitudinal edge of which is folded to form a rearwardly and inwardly or laterally inclined section 12 that is terminally formed in a return bend 13, then projected as a section 14 in spaced parallel relation to the section 12, the section 14 terminating in a return bend 15 and projected as a rearwardly and inwardly extending section 16 in spaced parallel relation to the section 14, the end of the section 16 projected rearwardly to form a web section 17 extending substantially at right angles of the face portion 10, the section 17 terminating in an inclined edge flange 18. The sections 12, 14 and 16 are substantially in parallelism providing channels 19 and 20 of a width substantially equal to the thickness of the sheets of which the units are formed. The upper and lower edges of the web section 17 of the unit 2 are formed with vertically extending slots 21 of a width substantially equal to the thickness of the sheets from which the units are formed.

In forming a wall from the above described members, the auxiliary units 2 are utilized as the connecting medium between adjacent main units 1. When assembling these main and auxiliary units, as best shown in Figs. 2 and 4, the section 7 of the main unit 1 is inserted in the channel 20 of the adjacent auxiliary unit 2 while, at the same time, the flange 11 of the auxiliary unit seats within the rearwardly extending offset 5 of the locking unit 3.

main unit. The section 9 of the adjacent main unit 1 is inserted in the channel 19 between the sections 12 and 14 of the auxiliary unit 2. In this position, the offset 8 of the second mentioned main unit 1 seats squarely against the shoulder or return bend between this face 10 and the section 12 of the auxiliary unit 2 and the flange section 9 forms a lock with the channel forming sections 12 and 14 against the lateral separation of the main unit and the auxiliary units. A complete wall may thus be formed by assembling the desired number of main units, 1 with the intermediate retaining units 2, the face sections 4 and 10 lying in the same plane to form a wall transversely of the building and the web sections 17 forming joists for the wall.

One of the advantages of the present invention resides in the adaptability of the units for cooperation to form all of the planar surfaces in a building, that is, the inner walls, the partitions, the floors, the ceilings and the roof, as well as the outer wall. The inner wall is assembled in the identical manner except, in this instance, the front surfaces of the main units form the inner surface or face of the inner wall. A double wall construction is shown in Fig. 2 as constituting an outer wall A formed by assembled units 1 and 2, and an inner wall B formed by assembled units 1a and 2a which may be identical in conformation to the units 1 and 2 but for convenience in description are identified herein by the character "a." In this arrangement the web portion 17 of the auxiliary units 2 constituting the uniting members of the outer wall A extend toward but terminate short of the inner surface of the inner wall B, and the web sections 17a of the auxiliary units 2a of the inner wall B will extend toward the front wall A and in parallel and slightly spaced relation with the webs 17 of said front wall. The webs 17 and 17a are spaced to receive an insulating strip 23, which may be of any conventional or appropriate material, and thereby break thermal contact between the outer wall A and the inner wall B.

It will be noted that the double wall construction provides intermediate spaces 24 separated one from the other and that there is no material metallic contact between any portion of the inner wall structure and any portion of the outer wall structure. This avoidance of metallic contact serves in itself as an effective insulation, to say nothing of the air contained in the inter wall spaces 24. In addition to their function for insulating purposes, the spaces 24 may conveniently accommodate installation of electric wires, pipes or other accessories with complete protection, simplicity of installation and removal, while being completely invisible or unobstructed from the interior of the building.

The outer and inner wall formations and the parts forming the same may be locked in a fixed predetermined relation against the possibility of displacement or separation, by any suitable means, however, the locking unit 3, shown in Fig. 1, is preferred as it also functions in the manner of a plate at the ends of the webs 17 and 17a which function as studs. This unit comprises a channel-like member having a face 26 with angularly extending inner and outer edge flanges 27 and 28, with appropriately spaced and formed cut-out defining slots. These locking units 3 are provided throughout the length of each outer and inner wall at the top and bottom, and are positioned with their faces 26 horizontal and their flanges 28 in contact with the inner surfaces of

the bodies or faces 4 and 10 of the main units 1 and the auxiliary units 2 respectively. The flanges 28 are provided with slots 29 extending inwardly to the faces 26, and which are spaced to straddle the angle portions extending rearwardly from the face portions of the main and the auxiliary units. The inner flange 27 is arranged to overlie the edges of the web portions 17 and 17a of the auxiliary units and is provided with slots 30, each to straddle a web portion 17 and 17a of the auxiliary units 2 and 2a, the width of the face section 26 of the locking unit being such that when applied the slot 30 will accurately register with the slots 21 in the web portions 17 and 17a. The relative depths of the slots 21 and 30 is such that when the locking unit is applied as described, the slots 30 on the locking unit 3 actually engage the unbroken material of the web 17 of the auxiliary unit 2 and the slots 21 in the auxiliary unit engage the unbroken portion of the flange 27 of the locking unit 3. Thus, the face section 26 of the locking unit rests against the end edges of the interlocking flanges extending from the main units 1 and of the auxiliary units 2 and as the slots in the parts actually engage unbroken portions of the cooperating elements, the webs 17 and 17a of the auxiliary units 2 and 2a are rigidly braced against angular movement and the web portions 17 and 17a are maintained in fixed, spaced parallelism without other support or fastening.

The locking units 3 are assembled at the upper and lower ends of the wall structures and against the inner surfaces of both the inner and outer walls, as indicated in broken lines in Fig. 2. Consequently, the parts, without substantial metal contact and without the use of additional fastening or securing means, are locked against separation, maintaining them in their fixed desired position against any usual strain to which the walls may be subjected. Thus, the locking members, when in applied position become a part of the wall structure locking such parts together at the top and bottom, preventing the possibility of their casual separation or movement in any direction and, furthermore, forming plates at the bottom for supporting the wall on a suitable base, and at the top for supporting any desired superstructure.

While the building may be mounted on any appropriate foundation, it may be advantageously employed with a particular foundation, best shown in Fig. 3. This foundation comprises vertically positioned I-beams 31, having their sides cut away at their upper ends to provide each with a tongue 32 that is formed by the web of the beam. The main length of the I-beam is sunk in the ground or embedded in a cement foundation and the upstanding tongue 32 is inserted between the lower ends of the spaced webs 17 and 17a of the auxiliary units 2 and 2a. The contacting surfaces of the tongue 32 and webs 17 and 17a of the auxiliary units 2 and 2a are provided with one or more openings through which an appropriate fastening element may be inserted. The foundation beams 31 preferably cooperate with the lower ends of each pair of auxiliary units 2 and 2a, but, obviously, they may be arranged in less number under reduced weight requirements.

The cutaway portions of the outer sides of the I-beams 31 present side shoulders 33 to receive and support the locking units 3 at the lower edges of the outer wall A, whereas the I-beams 31 are cut away on their inner sides to a point below the level of the shoulders 33 to provide secondary

shoulders 34 to support the floor beams as herein-after described.

The floor of the structure may be constructed in a manner identical to that of the walls, and 5 may comprise main and auxiliary units which are of the same conformation but, for convenience, are identified by the character "b." If the building is of double wall type, the edge of the floor, preferably, will be formed to extend beyond the 10 inner wall, whereas, if it is of the single wall type the floor will be extended to the outer wall. The floor structure comprises a plurality of main units 1b connected by intermediate auxiliary units 2b, the webs 17b of which extend downwardly to 15 form beams. The ends of the faces and lock forming sections of the auxiliary units 2b are cut away to provide an extended portion 35 of the webs 17b so that the cut-away end edges may 20 more or less abut the inner edge of the tongue 32 and the extended portion 35 may be placed against the web of the I-beam and the free edge of the flange 18b of the web 17b may rest on the shoulders 34 of the I-beam. The extended portion 35 may be fixed to the I-beam by any appropriate fastening to form a rigid connection.

The main units 1b are cut away at the ends of their locking edges to coincide with the cut-away portions of the auxiliary units 2b, the body 4 of the main units 1b forming projecting portions 38 having their edges upturned to form flanges 39, as best shown in Fig. 5. When the main floor units 1b are in position, the projecting end portions 38 will underlie the locking units 3a of the inner wall B and the flange 39 will lie 30 behind and in contact with the free side of the inner locking units 3a to lock the floor and inner wall structures together. The lower edges of the projecting portion 35 of the auxiliary units 2b are so related to the web of the I-beam as to rest 35 on the inner shoulders 34 on the I-beams 31, and bear against the tongue 32 to support and tie 40 the floor as a whole on and to the foundation beams 31. The opposite edge of the floor structure will be identical with that just described and 45 need not be repeated.

The construction at the corners is identical with that hereinbefore described except that the corner pieces 25 are formed by main units that have their body portions 4 longitudinally bent at 50 an angle intermediate their longitudinal edge formations to permit one edge portion of the main unit to extend as a part of one wall and the other edge portion to extend as a part of the other wall.

In order to insure and maintain the rigidity of 55 the corners of the building, corner braces 40, shown more particularly in Figs. 2 and 6, are provided between the adjacent webs 17 or 17a of the auxiliary units 2 or 2a adjacent the corners. These corner braces include an integral member 60 having side walls 41 and a center wall 42 with the side walls 41 at right angles so as to bear squarely against the respective webs 17 or 17a and the center wall 42 will extend between said webs as a brace. The side walls 41 are braced by integrally formed cross partitions 43. The side walls 41 are provided with key-hole slots 44 and the webs 17 or 17a, with which the side walls 41 contact, are provided with headed lugs 45 projecting therefrom and adapted for locking engagement through the key-hole slots 44, in a conventional manner, as best shown in Figs. 7 and 8.

The ceiling structure is again made up of the main and auxiliary units of the same conformation as herein before described and which are 70 connected in exactly the same manner as previ-

ously described; however, as a matter of convenience the units forming the ceiling are identified by the character "c." In this instance, however, the portions of the main units constituting the outer face of the wall are arranged to constitute the face of the ceiling. Here, the main units 1c, when in position, extend over the edges of the inner wall B, but the body portions thereof do not cover the space between the inner wall B and outer wall A, as shown in Fig. 4. The ends of the body portions 4c of the main units 1c of the ceiling structure overlie the inner wall B and the adjacent inner locking unit 3a, and the end edges thereof are turned down to form flanges 46 to rest behind and in close contact with the relative outer surfaces of the locking units 3a, thereby locking the upper edges of the inner wall B with the ceiling in the same manner as previously described with respect to the floor.

The ceiling sections proper, that is, the main units 1c are interlocked with the auxiliary units 2c in usual manner and while the major portions of the main units 1c extend only over the inner wall, the auxiliary units 2c extend to the outer wall. In other words, the auxiliary units 2c have their ends extended to overlie and align vertically with the auxiliary members 2 and 2a of the outer and inner walls A and B, respectively. This arrangement provides means for interlocking the ceiling with the wall structure.

The web portions 17 and 17a of the auxiliary units 2 and 2a in the walls A and B are extended to form tongues 54 and 55 rising above the level of the ceiling. The face portion 10 of the extended end portion of the auxiliary units 2c, as best shown in Fig. 4, is provided with spaced, parallel longitudinally extending slots 48 and 49, and the sections 16c and 18c extending angularly from each side of the web 17c are provided with slots 59 and 51, respectively, adjacent to the surface of the web 17 and in alignment with the slot 48. In addition, the angular portions 6c of the main units 1c are provided with a pair of slots 52 and 53 to overlie and coincide respectively with the slots 48 and 49.

In assembling the ceiling, each auxiliary unit 2c is positioned so that the slots 48 and 49 register with the respective tongues 54 and 55 of the auxiliary units 2 and 2a of the outer and inner walls A and B. The tongue 54 may be longer and extend upwardly through the registering slots 48, 52, 59 and 51 and in substantial contact with one side of the web 17c of the auxiliary units 2c. The tongue 55 may extend through the registering slots 49 and 53 and into contact with the opposite side of the web 17c. The tongues 54 and 55 may then be fastened together with the web 17c sandwiched therebetween to securely tie the ceiling with the walls and to lock the parts in fixed relative position.

Each projecting end of the auxiliary units 2c in the ceiling assembly is formed to so interlock with the auxiliary units of the wall formation thereby providing a plurality of interconnections by which the ceiling structure is locked to the wall structure. Furthermore, it will be apparent that one of the extended tongues 54 and 55 rises as a continuation of that auxiliary unit 2 forming part of the outer wall A, while the other tongue rises as a continuation of the adjacent auxiliary unit 2a, forming part of the inner wall B. Therefore, when these tongues 54 and 55 are engaged in and through the slots of the auxiliary units 2c of the ceiling structure, it will be apparent that the adjacent webs 17 and 17a of the auxiliary

units 2 and 2a of the outer and inner wall are held in each instance in parallelism and positively locked against relative movement.

The roof, here shown in Figs. 3 and 4 as a gable roof, but obviously capable of arrangement in other, even flat, forms if desired, again utilizes the main and auxiliary units as the primary elements in its construction, which, for convenience are identified by the character "d." Each side or section 57 and 57' of the gable roof, is made up of main units 1d and auxiliary units 2d and with the webs 17d depending therefrom to act as rafters. The outer ends of the auxiliary units 2d of the roof assembly are provided with slots 58 in the flanges 18d and adjacent the surface of the webs 17d. The roof may then be mounted above the ceiling and tied to the wall structure by the extended portion of the longer tongue 54 of one of the auxiliary units 2 or 2a forming the wall structure. The tongue 54 projects through the slots in the ceiling structure and is extended to pass through the slot 58 of the auxiliary unit 2d of the roof assembly. The extended tongue portions 54 of the webs 17 or 17a of the auxiliary units 2 or 2a that are employed in the wall assembly, thus extend upwardly through the outer ends of the auxiliary units 2c of the ceiling assembly and the outer or lower ends of the auxiliary units 2d of the roof assembly to tie the walls, the ceiling and the roof in fixed relative position. The outer ends of the roof units 1d and 2d may be cut away at an inclination to correspond with that of the roof section and to be in a vertical plane with the ends of the ceiling structure.

35. The meeting ends of the roof sections 57 and 57', at the apex of the roof, are connected by a locking channel 3d, shown more particularly in Figs. 3 and 9. The channel 3d comprises a flat face plate section 60 and relatively inclined parallel side flanges 61 having slots 62 to register with the slots 21d in the end of the web portions 17d of the auxiliary roof units 2d. The face sections 60 are, preferably, somewhat wider than the regular locking units 3 to extend between the slots 21d in the webs 17.

Two such locking channels 3d extend lengthwise of the roof at the meeting edges of the webs of the roof sections at the apex of the roof. The channels 3d are positioned with their plate sections 60 in contact and their slots 62 registering with the slots 21d of each of the webs 17d of the auxiliary units 2d.

55. The locking channels 3d may be rigidly connected as a single unit though this is not absolutely essential for the purpose of the reinforce and binding. These locking channels interlock all auxiliary units of each roof section, 57 or 57', binding the auxiliary units 2d of these sections together and rendering the structure at the apex of the roof immovable and rigid. The main units 1d forming the roof sections 57 and 57' are provided at their apex ends with upwardly turned U-shaped flange portions 63. A rigid seal 64 having lateral downwardly turned U-shaped flange portions 65, is arranged to interlock with the flanges 63 at the apex end of each roof section 1d to bind these sections in rigid relation and at the same time cover and effectively seal the joint between them.

Similar locking channels 3e may be provided to tie together the free outer ends of the roof and ceiling sections and along the length of the building. These channels 3e are substantially identical to the channels 3d with the exception that the side flanges 61' are at right angles to the face

plate 60'. The slots 62' in these side flanges 61' are so arranged, and the width of the locking channels 3e is such that the slots 62' in one flange 61' will cooperate with slots 66 in the web portions 17c of each and every auxiliary unit 2c forming part of the ceiling assembly. Likewise, the slots 62 in the other flange 61' cooperate with the slots 67 in the webs 17d in the auxiliary units 2d which form part of the roof sections. As the locking channels 3e and the webs 17 of the auxiliary units are interfitted to the limit of their respective slots, there is rigid metal to metal bearing between the parts which maintain the auxiliary units in proper position and lock them against lateral movement.

It is to be particularly noted that through the arrangement described, the auxiliary units 2d of the roof section assemblies act as the top cords or compression members of a roof truss, the bottom truss or tension member of which cord is formed by the auxiliary units 2c of the ceiling assembly.

The upper edges of the main units 1 of the outer wall A are formed over to provide downwardly extending hooks 68 and the ends of the auxiliary units 2d of the roof section assemblies are formed over to provide upwardly extending hooks 69. These hooks throughout the length of the building are united by a facia sheet 70 having edge hook portions 71 to slidably cooperate with the respective hooks 68 and 69, in a manner to prevent relative upward movement of any of the portion of the building above the walls, while at the same time providing an ornamental finish for the building structure. If desired, a gutter structure 72 may be arranged to interfit over the upper end of the facia sheet 70, as shown in Fig. 4, to overlie the lower side edges of the roof sections for drainage purposes.

Preferably, but not necessarily, the outer wall structure A may extend the full height of the building, while the inner wall structure, at the ends of the building, terminates at the ceiling line.

Although certain specific embodiments of the invention have been shown and described, it is obvious that many modifications thereof are possible. The invention, therefore, is not to be restricted except insofar as is necessitated by the prior art and in accordance with the scope of the appended claims.

What is claimed as new is:

1. A building surface structure for forming a wall floor, ceiling or roof of a building, which structure includes a plurality of units of three types, two types of said units having face portions to form a surface, and flanges and channels respectively formed along their adjacent edges and interfitting in locking engagement to join said units together with their face portions in a plane, one of said two types of units having rearwardly extending web portions to rigidly brace said units longitudinally, the third type of said units comprising a locking member extending transversely of a plurality of said two types of units and locking said units together, said locking member having means for clipping the interfitting angular flanges and the web portions of said units to lock those parts together and brace the assembled structure transversely of said units.

2. A building structure as set forth in claim 1 wherein said locking member comprises a channel structure having parallel flanges, slots in one of said flanges and straddling the interfitting

flange and channel forming portions of said units, and slots in the other of said flanges and straddling the rearwardly extending web portion to rigidly hold said web at a predetermined angle.

3. A building structure as set forth in claim 2 wherein the web straddling slots of said locking member extend only part of the depth of said flange and the webs are provided with slots in their ends to receive the remainder of said flange at the ends of its partial depth slots.

4. A double surfaced building structure for forming a double wall or a ceiling and floor or the like, which structure includes spaced surface constructions, each of which comprise a plurality of units having face areas and with their adjacent edges respectively formed with interlocking flanges and channels which are assembled to position said face areas in a plane to form a surface, alternate units having a rearwardly extending web to brace said units longitudinally, said spaced surface structures being arranged back to back with said rearwardly extending webs extending in opposite directions and in side by side relationship, and a locking member extending longitudinally of and between said spaced surface structures and clipped over said webs to lock said structures as a unit.

5. A roof structure comprising two sections as 30 a gable roof, each of said sections comprising a plurality of units, two types of said units having face portions to form a surface, and flanges and channels formed along their adjacent edges and interfitting in locking engagement to join said 35 units together with their face portions in a plane, one of said two types of units having rearwardly extending web portions to rigidly brace said units longitudinally, the third type of said units comprising a locking member extending transversely 40 of a plurality of said two types of units and locking said units together, said locking member having means for clipping the interfitting angular flanges and the web portions of said units to lock those parts together and brace the assembled 45 structure transversely of said units, the adjacent edges of the face portions of said sections being formed upwardly and over to form locking flanges, and an angular channel member spanning the joint between said sections and having 50 returned flanges underlying and locking with said locking flanges.

6. A building structure comprising a wall made up of main and auxiliary units having edge interlocking formations maintaining body portions of 55 the main units in the same plane and web portions of the auxiliary units at right angles thereto in the manner of studs, some of the webs of the auxiliary units forming the wall extending upwardly, and a roof structure made up of units 60 having the same configuration as the wall units with the body portions of the main units and parts of the interlocking formations of the main and auxiliary units forming the surface of the roof and the webs of the auxiliary units extending 65 downwardly, the top edges of the body portions of said wall units being formed over as downwardly extending flanges, extensions of the webs of the roof units being formed over as upwardly extending flanges, and a face plate covering the ends of said roof webs and having inwardly turned edges fitting around said body and web flanges.

7. A building structure comprising a wall made 75 up of main and auxiliary units having edge interlocking formations maintaining body portions of

the main units in the same plane and web portions of the auxiliary units at right angles thereto in the manner of studs, and a floor section made up of main and auxiliary units having the same cross-sectional configuration as the units making up the wall, the web portions of said floor units extending downwardly in the manner of beams, and a foundation comprising vertically positioned I-beams having their side flanges cut away at their upper ends to form tongues extending upwardly into contact with the web portions of said wall units, said wall units being supported by the shoulders formed by the cut away side flanges on the outer sides of said beams, the web portions of said floor units bearing in edge engagement on the shoulders formed by the cut away side flanges on the inner sides of said beams and contacting in surface engagement with the webs of said beams.
